CLAIM

I claim the ornamental design for a cosmetic abrasion device, as shown and described.

DESCRIPTION

FIG. 1 is a top, right, front perspective view of an embodiment of the claimed design;

FIG. 2 is a top, left, rear perspective view thereof;

FIG. 3 is a front elevation view thereof;

FIG. 4 is a rear elevation view thereof;

FIG. 5 is a left elevation view thereof;

FIG. 6 is a right elevation view thereof;

FIG. 7 is a top plan view thereof; and,

FIG. 8 is a bottom plan view thereof.

The ornamental design which is claimed is shown in solid lines in the drawings. The broken lines immediately adjacent the solid contour lines in FIG. 8 illustrate the bounds of the claim. The remaining broken lines illustrate portions of the cosmetic abrasion device. None of the broken lines forms part of the claimed design.
